ELECTRIC LIGHT FIXTURE

Clyde Poling, Fairmont, W. Va., assignor to West Virginia Lighting Co., Inc., Fairmont, W. Va., a corporation of West Virginia

Application April 16, 1937, Serial No. 137,330

4 Claims. (Cl. 240—78)

This invention relates to light fixtures and more particularly to a direct lighting fixture of the hanging or suspension type.

The object of the invention is to provide a direct lighting fixture of simple and inexpensive construction capable of being readily attached to the ceiling of a room or other enclosure and which will diffuse light in soft mellow rays free from glare and dazzling radiance and thus insure maximum illumination and visibility with minimum danger of eye strain.

A further object of the invention is to provide a lighting fixture including a supporting frame having an upper ring and a bowl-retaining ring rigidly connected by inclined braces, said retaining ring being circumferentially stepped to produce offset portions constituting seats for the upper and lower bowls of the light fixture.

A further object is to utilize the fastening devices between the inclined braces and retaining ring for holding the lower bowl or globe to its seat in the adjacent offset portion of the retaining ring whereby positively to prevent accidental displacement of said bowl under all conditions of service.

A still further object of the invention is generally to improve this class of devices so as to increase their utility, durability and efficiency.

In the accompanying drawings forming a part of this specification and in which similar numerals of reference indicate corresponding parts in all the figures of the drawings:

Figure 1 is a front elevation of an electric light fixture embodying the present invention.

Figure 2 is an enlarged vertical sectional view taken on the line 2—2 of Figure 1, the hanger and its associated parts being shown in elevation,

Figure 3 is a transverse sectional view taken on the line 3—3 of Figure 2 with the upper globe and light socket removed, and

Figure 4 is an enlarged detail vertical sectional view showing the manner of clamping the lower bowl or globe to its seat.

The improved electric light fixture forming the subject-matter of the present invention comprises a tubular hanger 5 of any desired length having its upper end provided with a canopy 6 for attachment to a ceiling or other suitable support and its lower end fitting with a socket 7 for the reception of an electric light bulb, indicated at 8. Surrounding the socket 7 is a casing 9 having one or more lateral fingers 10 riveted or otherwise rigidly secured thereto and adapted to fit beneath a bead or flange 11 formed on an annular member or ring 12.

Spaced from the annular member 12 and rigidly connected thereto by inclined braces 13 is a retaining ring 14 of greater diameter than the ring 12 and provided with circumferential steps or offset portions 15 defining seats 16 and 17 adapted to receive the upper and lower bowls 18 and 19, respectively, of the light fixture. The upper seat 16 is disposed in a horizontal plane so as to permit the peripheral edge of the bowl 18 to rest flat against the seat while the lower seat 17 is inclined downwardly to conform to the shape of the lower bowl 19. The opposite ends of the inclined braces 13 are given a half twist to provide terminal lugs 20 for the reception of bolts or similar fastening devices 21 and 22 whereby to connect the upper and lower rings together and form a strong rigid supporting frame for the glass bowls of the fixture. The lower fastening devices 22 extend through the retaining ring 14 and adjacent lugs 20 of the inclined braces 13 and are threaded for engagement with clamping nuts 23. By reference to Figure 4 of the drawings, it will be seen that the nuts 23 by engagement with the peripheral edge of the lower bowl 19 serve to hold the bowl firmly to its seat 17 and thereby effectually prevent accidental displacement thereof. The fastening devices 22 thus perform the dual function of securing the lower ends of the inclined braces to the retaining ring and locking the lower bowl to its seat. A finishing ring 24 preferably surrounds the beaded portion of the upper ring 12 so as to give the fixture a neat attractive appearance. The upper globe 18 is preferably formed of white translucent glass while the lower bowl 19 is constructed of pale blue glass with an inner white translucent face so that, when the bulb 8 is lighted, the light will be diffused in soft mellow rays free from glare and dazzling radiance and thereby insure maximum illumination and visibility without danger of straining or otherwise injuring the eyes. The threaded ends of the bolts 22 are preferably of sufficient length to form auxiliary stops so that in case the lower globe 19 does not contact the clamping nuts 23, the edge of the bowl will engage the threaded ends of said bolts and thus hold the lower bowl to its seat.

In assembling the different parts of the fixture, the lower bowl 19 is first positioned on its seat 17, after which the lower ends of the inclined braces 13 are fastened to the retaining ring by means of the threaded bolts 22 and in which position the nuts 23 will bear against the peripheral edge of the lower bowl and lock it to its seat in the manner before stated. The upper

bowl 18 is then fitted over the hanger 5 and allowed to rest on the flat seat 16 of said ring with its upper end resting on the flared lower portion 25 of the annular member 12, as best shown in Figure 2 of the drawings. The socket casing 9 is then positioned on the annular ring 12 by introducing the ears 10 within said ring and causing them to engage beneath the bead 11, after which the finishing ring 24 is positioned over the bead 11 and the hanger and canopy are attached to the ceiling in any desired manner. In order to remove or replace the electric light 8, it is merely necessary to elevate the upper bowl or globe 18 when access may be readily had to the socket 10, as will be readily understood.

An electric light fixture constructed in accordance with the present invention is strong and durable and will effectually support the glass globes of the fixture against accidental displacement and breakage under all conditions of service.

Having thus described the invention, what is claimed as new is:

1. A lighting fixture including a supporting frame having upper and lower rings, one of which is provided with circumferentially stepped portions defining a horizontal seat and an inclined seat connected by an intermediate flat vertical portion, inclined braces connecting said rings and having their lower ends bearing against said intermediate flat portion, a lower bowl resting on the inclined seat, an upper bowl resting on the horizontal seat, and fastening devices extending through the stepped ring and the adjacent braces and bearing against the peripheral edge of the lower bowl for preventing accidental displacement thereof.

2. A lighting fixture including a supporting frame having upper and lower rings, one of which is provided with circumferentially stepped portions defining a horizontal seat and a downwardly and inwardly inclined seat connected by an intermediate flat vertical portion, inclined braces connecting said rings and having their opposite ends twisted to form attaching ears for

engagement with the adjacent rings, a lower bowl resting on the inclined seat and an upper bowl engaging the horizontal seat, threaded bolts extending through the stepped ring and the attaching ears of the adjacent braces, and nuts 5 threaded on said bolts and bearing against the peripheral edge of the lower bowl for holding said bowl to its seat.

3. A lighting fixture comprising a supporting frame including upper and lower rings, one of which is provided with an inclined flange and the other with circumferentially stepped portions defining an upper horizontal seat and a lower inclined seat connected by an intermediate flat vertical portion, braces forming a connection between the rings, an upper bowl having its lower edge resting on the horizontal seat and its upper end bearing against the inclined flange of the adjacent ring, a lower bowl resting on the inclined seat, and fastening devices extending 15 through the stepped ring and the adjacent braces and bearing against the lower bowl for holding said lower bowl in engagement with said inclined seat.

4. A lighting fixture comprising a supporting frame having an upper ring formed with a terminal laterally extending flange and a lower retaining ring circumferentially offset to form a horizontal upper seat and a downwardly and inwardly inclined lower seat connected by an intermediate vertically disposed flat portion, spaced 25 braces forming a connection between said rings and provided with terminal attaching ears, an upper bowl engaging the horizontal seat and flange of the upper ring respectively, a lower 30 bowl resting on the inclined seat, threaded bolts extending through the flat intermediate portion of the retaining ring and having their inner 35 threaded ends projecting over the peripheral edge of the lower bowl, nuts engaging the threads on 40 the bolts, said nuts engaging the edge of the lower bowl and serving to hold said bowl to its seat, and a hanger operatively connected with the upper ring for attachment to a support.

CLYDE POLING. 45
